EYE TESTING DEVICE

Robert V. Gerhardt, Rochester, N. Y., assignor to Bausch & Lomb Optical Company, Rochester,
N. Y., a corporation of New York

Application February 17, 1951, Serial No. 14,259

Term of patent 14 years

(Cl. D57—1)

To all whom it may concern:

Be it known that I, Robert V. Gerhardt, a citizen of the United States and a resident of Rochester, county of Monroe, and State of New York, have invented a new, original, and ornamental Design for Eye Testing Device, of which the following is a specification, reference being had to the accompanying drawing, forming a part hereof.

Fig. 1 is a perspective view of the front and one side of an eye testing device, showing my new design, the dotted-line showing of the slides being omitted for convenience of illustration.

Fig. 2 is a similar view showing the top and rear portions of the device.

Fig. 3 is a view showing the other side of the device.

I claim:

The ornamental design for an eye testing device, substantially as shown.

ROBERT V. GERHARDT.
